UNITED STATES PATENT OFFICE.

ABRAHAM GARBEIL, OF PHILADELPHIA, PENNSYLVANIA.

TOILET-BOX.

1,317,918.

Specification of Letters Patent.

Patented Oct. 7, 1919.

Application filed February 4, 1919. Serial No. 274,918.

To all whom it may concern:

Be it known that I, ABRAHAM GARBEIL, a citizen of the United States, residing at Philadelphia, in the county of Philadelphia 5 and State of Pennsylvania, have invented certain new and useful Improvements in Toilet-Boxes, of which the following is a specification.

One object of my invention is to provide 10 a neat and compact toilet box of the type generally known as "vanity boxes" and to so construct my improved box that it will conveniently hold, in different compartments, compressed portions of white or light 15 colored powder and rouge, so that a lady, by a slight movement of certain of the parts, can use either the powder or the rouge.

Another object is to provide my improved 20 box with reflecting means which is so arranged that a portion thereof may be readily seen when either the powder or the rouge is in position to be used.

A further object is to so construct my 25 improved box that it may be used to hold other toilet articles such as an eyebrow pencil, lip stick and vials of perfume.

A still further object is to so construct my improved box that it can be readily 30 opened and can be easily carried and manipulated.

These objects, and other advantageous ends which will be described hereinafter, I attain in the following manner, reference being had to the accompanying drawings in 35 which—

Figure 1 is a perspective view of a box made in accordance with my present invention and showing the same opened in a position to permit the use of the white or light 40 colored powder.

Fig. 2 is a perspective view of the box shown in Fig. 1, the box having been inverted and opened to permit the use of the rouge.

Fig. 3 is a sectional elevation of the box shown in Figs. 1 and 2 in its closed position.

Fig. 4 is a perspective view of a partition which forms a part of my improved box.

Fig. 5 is a central sectional elevation 50 showing a modified form of my invention.

Fig. 6 is a perspective view showing still another form of my invention.

Fig. 7 is a longitudinal sectional elevation of the box shown in Fig. 6 with the sections 55 arranged end to end so that either section can be opened, and

Fig. 8 is an outside elevation of the form of box shown in Figs. 6 and 7; the sections being folded one upon the other.

Referring to the form of my invention shown in Figs. 1 to 4, inclusive, 10 represents the body portion of my improved box which is open at its top and bottom and is provided between the top and the bottom 60 with a partition 11. This partition is preferably provided with flanges 12 which may be glued or otherwise secured to the inner surfaces of the body portion 10 so as to form a partition which divides the body portion 65 into two compartments 13 and 14. The corners of the partition 11 are cut away to provide recesses 15. These recesses, when the partition 11 is secured in position within the body portion 10, form holes through 70 which various toilet articles such, for example, as vials 16 and 17, lip stick 18 and eyebrow pencil 19 can be inserted. The vials 16 and 17 can be used to contain perfume or other material.

Cakes 20 and 21 of powder and rouge are positioned within the compartments 13 and 14, respectively, and are supported either by glue or other suitable means upon the partition 11. Puffs 22 and 23 are also contained within the compartments 13 and 14 and can be used to apply the powder and rouge to the face.

The compartment 13 can be closed by a cover 24 which is hinged at 25 to the body 90 portion 10 and has a flap 26 provided with a snap-button 27, whereby the cover can be closed and secured to the front of the body portion 10; said front also being provided with a portion of said snap-button. The compartment 14 can be closed by a cover 28 which is hinged at 29 to the bottom of the body portion 10. The cover 28 is also provided with a flap 30 having one portion of a snap-button 31 thereon; the other portion of 100 said snap-button being attached to the front of the body portion adjacent the bottom.

Thus, by the covers 24 and 28, the compartments 13 and 14 can be closed and will thus retain the removable parts within the box. The cover 24 has a mirror 32 on its inner surface and the cover 28 has a mirror 33 on its inner surface. The corners of the body portion 10 are cut away, as shown at 34, to permit the vials 16 and 17, lip stick 18 and eyebrow pencil 19 to be easily grasped by 10 the fingers and removed, for use, from the box.

In the use of the box shown in Figs. 1 to 4, inclusive, if it is desired to secure access to the powder 20, the cover 24 is opened into the position shown in Fig. 1. The puff 22 can be removed and the mirror 32 will be in proper position to permit view thereof. Also, either of the vials 16 and 17 can be freely removed as can the lip stick 18 and 20 eyebrow pencil 19. If it is desired to use the rouge 21, the cover 24 can be closed and the cover 28 can be opened, for example in the position shown in Fig. 2, merely by inverting the body portion 10. The mirror 33 will then be in position to be used and the puff 23 can be readily removed to apply the rouge.

In the form of my invention shown in Fig. 5, the parts are substantially the same as that shown in Figs. 1 to 4, inclusive, with the exception that instead of having the covers hinged at the top and bottom of the rear of the body portion, they are hinged at opposite ends of the body portion. For example, 35 the covers 35 and 26 which correspond in function to the covers 24 and 28 are, respectively, hinged at 37 and 38. Also, in the form of the invention shown in Fig. 5, the partition 39 which corresponds in function 40 to the partition 11, above described, has a hole 40 extending therethrough and the cakes 41 and 42 of powder and rouge can be molded so that a neck 43 extends through the hole 40 and thereby links the two cakes 41 and 42 together, at opposite sides of the partition. In all other respects, the construction 45 of Fig. 5 is similar to that described in Figs. 1 to 4, inclusive, and I have, therefore, given similar parts corresponding reference numerals.

In the form of my invention shown in Figs. 6, 7 and 8, I provide two box sections 44 and 45. These sections are hinged together at 46. A single cover 47 is secured to the hinge 46, as shown at 48, and has sections 49 and 50 for covering the box sections 44 and 45. The sections 49 and 50 are, respectively, provided with flaps 51 and 52. These flaps have snap-button sections 53 and 60 54 which can be secured to other snap-button sections 55 and 56 on the ends of 57 and 58. The cover section 49 has a mirror 59 on its underside and the cover section 50 has a mir-

ror 60 secured to its underside, as clearly shown in Figs. 6 and 7. Either of the cover sections 49 and 50 can be opened when the sections are arranged, as shown in Figs. 6 and 7. The box section 44 has a cake of powder 61 therein and a puff 62. The box section 45 has a cake of rouge 63 therein and 70 a puff 64. Thus either box section can be opened for use in applying the powder or rouge.

Fig. 8 shows the sections folded one upon the other so that the box thus folded can 75 be readily carried.

While I have described my invention as taking a particular form, it will be understood that the various parts of my invention may be changed without departing from the 80 spirit thereof, and hence I do not limit myself to the precise construction set forth, but consider that I am at liberty to make such changes and alterations as fairly come within the scope of the appended claims. 85

Having thus described my invention, what I claim as new and desire to secure by Letters Patent is:

1. A toilet box of the character described, including two compartments; cover portions 90 for respectively covering said compartments and reflecting means visible for reflecting purposes when either of said cover portions is opened to expose either compartment for use; substantially as described, 95

2. A toilet box of the character described, including a body portion open at its top and bottom; a partition within said body portion and positioned between said top and bottom whereby two compartments are formed; said 100 compartments being adapted to respectively contain cakes of powder and rouge; covers for closing the top and bottom of said body portion, whereby a closure is provided for said compartments; and means for securing 105 said covers in their closed position, whereby either of said covers can be opened independently of the other; said partition having recesses at its corners providing holes through which articles may be inserted so 110 as to be contained within said box, each of said covers serving as retaining means for preventing said articles from falling out of said box when the uppermost cover is open; substantially as described. 115

3. A toilet box of the character described, including a body portion open at its top and bottom; a partition within said body portion and positioned between said top and bottom whereby two compartments are 120 formed; said compartments being adapted to respectively contain cakes of powder and rouge; covers for closing the top and bottom of said body portion, whereby a closure is provided for said compartments; and means for securing said covers in their closed position. 125

tion, whereby either of said covers can be opened independently of the other; said partition having recesses at its corners providing holes through which articles may be inserted so as to be contained within said box; substantially as described.

5 In testimony whereof I have signed my

name to this specification in the presence of two subscribing witnesses.

ABRAHAM GARBEIL.
